UNITED STATES PATENT OFFICE.

FRANK E. ELLIS, OF REVERE, MASSACHUSETTS.

UNITARY PRINTER'S BLANKET.

1,311,596.

Specification of Letters Patent. Patented July 29, 1919.

Application filed April 28, 1917. Serial No. 165,148.

To all whom it may concern:

Be it known that I, FRANK E. ELLIS, a citizen of the United States, residing at Revere, in the county of Suffolk and State of Massachusetts, have invented new and useful Improvements in Unitary Printers' Blankets, of which the following is a specification.

The object of the present invention is to 10 simplify the mechanical methods of printing and reduce the expense of the essential equipment, by providing a blanket for use on the impression cylinder of a rotary printing press, which blanket serves as the sole 15 means for cushioning the impression cylinder.

To explain more fully the utility of my invention I will state that the impression cylinders of printing presses are of rigid 20 construction, being ordinarily cast iron, and that a yielding resilient packing or cushion is required to be placed upon their surfaces so as to support the paper while being 25 printed, compensating for errors in the printing plates and causing a uniform printed impression to be made at all points. Such printing plates, particularly the stereotype plates used in newspaper printing, are seldom truly cylindrical on their 30 printing surfaces, but usually contain high and low spots of greater or less magnitude which make impossible the production of a uniformly heavy and clear printed impression on the paper, unless the paper is supported in such a yielding and resilient manner 35 that it can give way under the impact of high spots in the plates, and is held up in contact with the type faces in the low spots thereof. For this reason it has been 40 the practice heretofore to pack or cushion impression cylinders with two or more blankets, as they are called, one being composed largely of vulcanized rubber and the other being a so-called felt blanket of woven 45 woolen fabric having a long felted nap. It has also been the custom, until the advent of an improved blanket recently produced by me, to overlay the felt blanket with a thin cotton cloth called a tympan cloth to 50 act as a blotter to absorb wet ink of the first impression on the paper when passing over the second impression cylinder. The purpose of this invention is to furnish a blanket 55 which will serve as the sole packing or cushioning means for the impression cylinder.

der, thereby supplanting the multiplicity of blankets and sheets heretofore required. This object is accomplished by providing a fabric or article having the firmness required to hold the paper against the printing plates combined with the resilience necessary to cause the impression produced from all parts of the plate to be substantially uniform. Another object is to combine with these features the further characteristics of not being injured by the oils contained in printers' inks, and of having a surface so repellent to ink, or at least so slightly adherent to or absorptive of ink, as not to become coated with ink deposited on one side 60 of the paper upon the first impression, when the blanket is used on the cylinder which supports the paper at the second impression. The invention therefore consists in a blanket 65 having the characteristics above broadly 70 stated together with special attributes hereinafter noted in detail.

In the drawings, Figure 1 is a sectional view of a fragment of printer's blanket embodying my present invention.

Fig. 2 is a cross section of the impression cylinder of a printing press having my new blanket applied thereto as the single unit packing for the cylinder.

Fig. 3 is a view similar to Fig. 1 showing 85 a modification in the construction of the blanket.

Figs. 1 and 3 are enlarged in scale and Fig. 2 is reduced in scale from the normal 90 actual dimensions.

The embodiment of my invention shown in Figs. 1 and 2 comprises a body *a* of granulated cork, the particles of which are joined together by a suitable binder, a backing *b* of textile fabric and a face layer *c* of a 95 nitrocellulose composition, preferably including sufficient castor oil or other non-drying oil in solution as an emollient to keep it flexible and prevent it from becoming brittle, and cracking. This blanket is applied to the impression cylinder of a 100 printing press indicated at *d* in Fig. 2, with the fabric backing layer or surface next to the face of the cylinder, and the nitrocellulose face exposed. It may be mounted and attached in any desired way and by any suitable means, preferably by the means long and commonly used for mounting blankets on impression cylinders. The means here shown comprises pointed pins *e* projecting 105

from one side of a longitudinal groove in the face of the cylinder, and a take-up roll *f* mounted in this groove and capable of being rotated by an externally applied crank, in connection with a pawl or equivalent means for preventing backward rotation. One end of the blanket is engaged with the pins *e* and the other end, after being passed around the cylinder, is attached to a flap *g* on the take-up roll *f*, and the latter is turned so as to stretch the blanket to whatever degree is necessary to remove wrinkles and prevent wrinkles forming in use.

The blanket here described possesses the following characteristics and useful features. The material of which the body is made is elastic, resilient, and compressible to a high degree and thus has the qualities necessary to support paper against the pressure applied by a printing plate, permitting the paper to yield wherever necessary, as when high points of the plate come against it, without being broken, and to return the paper when such high points have passed by, thus holding it always with sufficient and adequate pressure in contact with all parts of the plate in turn. At the same time this body, being of a manufactured conglomerate, may be made as thick or as thin as desired, wherefore a single blanket may be made to perform the functions of the plurality of blankets heretofore used. The backing layer is of textile fabric, which is firmly united over its entire surface by adhesive to one face of the body, giving strength to the blanket, taking the strain when the blanket is stretched around the cylinder and preventing the body layer from parting. The face layer or coating *c* has a two-fold function. One is that of lending strength to the blanket. This layer is preferably formed by applying successive films of nitrocellulose solution in the liquid or semi-liquid state and allowing the volatile solvent therein to evaporate between applications. In this way the coating may be built up to as great a thickness as desired. This material, nitrocellulose, has considerable tensile strength, and when combined with an emollient as I prefer to use it, is flexible and tough, but not brittle. It thus adds much to the strength of the entire blanket, preventing the body from cracking and parting at its exterior, but yielding under the pressure of high points in the printing surface, and maintaining a continuous, smooth, surface in contact with the paper. The other function of the face layer is to prevent offsetting of ink from the first impression on the paper when the second impression is being made. In a continuous rotary press the paper web, immediately after passing the first impression, goes to the second impression and at that time the side which was printed upon at the first im-

pression comes next to the second impression cylinder before the ink has had time to dry. The capacity of the ordinary printer's blanket to remove wet ink from the paper is so great that previously it has been necessary to provide a special covering of cotton cloth, called a tympan cloth, to act as a blotter to absorb surplus ink. These tympan cloths quickly become saturated with ink and must be discarded when the degree of saturation is such as to cause return of ink to the paper. The nitrocellulose face layer is so non-adhesive of, or repellent to ink that the undried ink on the paper will not adhere to it at all. Thus it does not carry, or "off-set," ink from one part of the paper web to a following part of the web.

The modification shown in Fig. 3 differs from the construction shown in Fig. 1 in that the textile fabric layer *b* is interposed between two layers *a'* and *a''* of the body. It might be said that the fabric is incorporated within the substance of the body, inasmuch as it is firmly united by adhesive to the body material on its opposite faces. This blanket is provided with a face layer *c* the same as that shown in Fig. 1. The purpose of this modification is to show that the position of the textile fabric layer or sheet may be changed within the scope of the invention, being placed in any desired location between the back face of the body and the surface layer *c*. The function of the textile layer being to give strength, it may be placed in any position where it answers that purpose to the best effect.

While the materials which I have hereinbefore named for the elements of the blanket are preferred, and are claimed as part of my invention, I do not restrict the invention thereto, but include within my claims a blanket having the essential characteristics herein defined whatever may be the materials out of which it is made. Thus any material having the qualities of compressibility, resilience, and elasticity, approximating those of cork conglomerate, may be used for the body; any material having smoothness, toughness, and non-adhesive qualities approximating those of nitrocellulose may be used for the face or surface layer; and any material having strength and flexibility approximating those of suitable textile fabric may be used for the strengthening layer or sheet *b*.

A blanket having the composition described not only has the characteristics already pointed out, but it does not absorb oil or ink and is therefore not deteriorated or otherwise affected by the oils contained in printers' inks. It is also little affected by the pounding or impact action of repeated impacts by the printing cylinder or by surface friction with the paper, wherefore it has long life. Finally it is relatively inex-

pensive to manufacture as compared with the rubber and felt blankets commonly used.

What I claim and desire to secure by Letters Patent is:

- 5 1. A unitary printer's blanket or impression cylinder packing comprising a body having resilience and elasticity, a strengthening layer having greater tensile strength than said body and being flexible, united thereto, and a face layer on the outer surface of said body, said face layer being tough and flexible, non adhesive to ink, and being smooth and homogeneous as to its outer surface; said blanket being adapted for use as the sole 10 packing of a printing press impression cylinder and to be so used with the said face layer uppermost.
- 15 2. The combination with the impression cylinder of a printing press, of a unitary packing comprising a body having elastic compressibility, a strengthening layer united to said body, and a face layer applied on the outer surface of the body and being tough, flexible, smooth, and nonadhesive to ink, one 20 face of said packing being in contact with the impression cylinder, and the said face layer being outermost and arranged to make contact with the paper web passing over the impression cylinder when being printed 25 upon.
- 30 3. A printer's blanket adapted to serve alone as the entire packing for a printing press impression cylinder, comprising a body of material which has resilience and elasticity approximating that of cork, and having united directly on the face of said body which is exposed to the paper being printed a surface layer of material which contains nitrocellulose and an emollient non-

drying oil, and is impervious, tough, flexible 40 and repellent to printers' ink.

4. A printer's blanket comprising a body having resilience and elasticity approximating that of cork, and having on the face exposed to the paper being printed a surface layer of material which is impervious, 45 tough, flexible and repellent to printers' ink and the blanket incorporating also in its structure a strengthening layer in a location between the face layer and the opposite side 50 of the body.

5. A unitary printer's blanket comprising essentially a body of granulated cork particles bound together and a face layer of tough and flexible nitrocellulose applied directly on the cork particles at one surface of the body, the side of the blanket opposite to the face layer being adapted for placement next to the surface of the impression cylinder, and the nitrocellulose layer being adapted 60 to bear on the paper being printed.

6. A printer's blanket comprising a body containing cork in its composition, a textile fabric strengthening layer or sheet adhesively united to said body, and a face layer of 65 tough and flexible non-brittle nitrocellulose deposited upon the outer surface of said body.

7. A printer's blanket comprising a cork body, a textile fabric strengthening layer or 70 sheet adhesively united to said body, and a face layer of nitrocellulose combined with a non-drying emollient united to the outer face of said body by deposition thereon as a 75 coating.

In testimony whereof I have affixed my signature.

FRANK E. ELLIS.
